UNITED STATES PATENT OFFICE.

DAVID G. McCAA, OF LANCASTER, PENNSYLVANIA, ASSIGNOR TO McCAA RADIO COMPANY, OF LANCASTER, PENNSYLVANIA, A CORPORATION OF PENNSYLVANIA.

ELECTRIC OSCILLATOR.

1,246,626.

Specification of Letters Patent. Patented Nov. 13, 1917.

Continuation of application Serial No. 65,106, filed December 4, 1915. This application filed October 30, 1916. Serial No. 128,448.

To all whom it may concern:

Be it known that I, DAVID G. McCAA, a citizen of the United States, residing in Lancaster, Lancaster county, State of Pennsylvania, have invented an Electric Oscillator, of which the following is a specification.

My invention relates particularly to apparatus for the production of oscillatory currents of high frequency and the emission 10 of electromagnetic waves.

As is known by those skilled in the art, a system of elevated conductors placed either above the earth or above a second system of conductors close to but insulated from 15 the earth possesses a definite capacity relation to the earth or to said system and is capable of receiving electrical energy and of storing it similarly to a condenser. If some means is provided of such a nature as 20 to permit the stored energy, upon reaching a certain maximum, to discharge into the earth or into a system near the earth, a circuit including the first system will have produced in it high frequency oscillations and 25 a portion of the stored energy will be radiated as earthed electromagnetic waves.

Heretofore the means usually employed for discharging the elevated conductor was a spark gap, which during the discharge became a part of the oscillator system in which an oscillatory current must necessarily flow. The spark gap, being of high resistance, caused a serious loss of energy and a material decrease in the number of oscillations 35 consequent upon each discharge, with a resulting increase in the decrement of the oscillations and the production of a wave of poor tuning qualities. Moreover, I have found that in radio telephony, a spark gap 40 in circuit with the microphone seriously interferes with the satisfactory functioning thereof.

One object of the present invention therefore is to provide a device for increasing the 45 energy storage function of the elevated conductors in an oscillator system, together with means whereby the oscillations produced in said conductors are transferred to said device, which itself shall operate without the inclusion of a spark gap.

It is further desired to provide an oscillator system capable of producing sustained oscillations of low decrement and of emit-

ting electromagnetic waves having good tuning qualities. 55

These objects and other advantageous ends I secure as hereinafter set forth, reference being had to the accompanying drawings, in which,

Figure 1 is a diagrammatic view illustrating a system for producing electro-magnetic waves in which the parts are arranged and connected in accordance with my invention; and

Fig. 2 is a diagram illustrating a slightly 60 modified form of the invention.

In the above drawings, 1 represents a source of current, 2 a device for making and breaking the flow of current in the circuit including said source and 3 the primary 70 winding of an induction coil. This latter is provided with a secondary winding 4 connected in a circuit including a condenser 5 and a quenched spark gap 6. It is obvious, however, that, without departing 75 from my invention, any other suitable current source and controlling means may be provided for setting up, limiting and cutting off current flow through said spark gap. 80

One terminal of the spark gap is connected to a plain open circuit radiating or main antenna 7—7, while its second terminal is connected through a coil 8 to the earth in such manner that the number of its turns 85 in circuit may be varied at will. This antenna will store energy according to the capacity relation between it and the earth and such relation will vary according to the type of said antenna, being smallest in a 90 straight vertical form and largest when the antenna belongs to the inverted or umbrella type. It is noted that this capacity relation is never very large and that the amount of energy stored before and radiated during 95 discharge is limited.

By long continued experiments I have found that the capacity relation and energy storage function of the system or circuit comprised by the parts 7—6—8, can be 100 greatly increased by arranging an auxiliary grounded conductor or series of conductors parallel to and intermeshing with the main conductors 7. With this idea in view I mount adjacent the latter a second series of 105 elevated conductors 9 connected to the earth

through a variable inductance 10 and a coil 11 adjustable as to the number of its turns in circuit, said coil being mounted to serve as the secondary of an oscillation transformer whose primary winding consists of the coil 8.

With such an arrangement of parts, the circuit 9-10-11 performs at least two desirable functions, of which the first is to increase the energy storage capacity of the circuit 7-6-8 during the charging of the latter;—and the second is to receive the oscillations developed in the circuit 7-6-8 and 9-10-11-8-6-7 and radiate the energy thus received during the discharge of said circuit. Another function is to form an oscillatory circuit consisting of the parts 9-10-11-8-6-7 which further increases the energy storage ability of the system, there being thus two capacities, *i. e.*, that existing between the antenna 7-7 and the earth augmented by the earthed conductors 9-9, and that existing between the antenna wires 7-7 and 9-9 independent of the earth connections. When the oscillations are set up in the circuit 7-6-8 by a discharge across the spark gap 6, which occurs upon the closure of the key 2, the primary winding 8 induces currents in the secondary winding 11, which currents are supplied to the auxiliary conductors 9, causing the circuit in which they are included to act as a radiating antenna in which no spark gap is present. The oscillations produced in this antenna are sustained and of low decrement and the waves emitted are sharp and of good tuning qualities.

It is particularly to be noted that owing to the presence of the system or circuit 9-10-11, there is no effectual radiation from the circuit 7-6-8;—the waves produced by the apparatus being emitted solely by the first named circuit when the adjustments of the coils 10-8-11 are such as to cause a maximum transfer of energy from the circuit 7-6-8 to the circuit 9-10-11.

If the current readings in the two circuits be taken, as by hot wire meters, when the above adjustments are made, I have found that a maximum current in the circuit 9-10-11 is accompanied by a minimum current in the circuit 7-6-8, and vice versa, the maximum reading in the circuit 7-6-8 occurs when there is a minimum reading in the circuit 9-10-11.

I have further found that the adjustments of the coils 8-11 and 10, in order to secure a maximum transfer between the two circuits may be made in two ways;

60 First;—By making the turns in the coil 8 the same as those in the coil 11 and thereafter varying the number of turns in the coil 10 until the maximum reading is secured, and

65 Second;—By altogether removing the coil

10, and varying the number of turns in the two coils 8 and 11, in which case the number of turns in the coil 8 must be greater than that in the coil 11.

I have found that for successful operation, the coils 8 and 11 must be so wound that any current entering them from the earth or from the aerial conductors will set up magnetic fields coinciding as to the direction of flux.

This relation of the windings causes the coils 8 and 11 to be non-inductive in the circuit 9-10-11-8-6-7, and the electrical equivalent of the system shown in Fig. 1, is found in Fig. 2 where said two coils 8 and 11 may be replaced by a single adjustable coil 12 connected between the earth and the point of junction of one end of the coil 10 and one terminal of the spark gap, in which case said single coil likewise serves as an oscillation transformer.

There are therefore two oscillatory systems supplying the radiating structure 9-10-11, for in Fig. 1, the circuit 7-6-8 supplies this structure by means of the oscillation transformer 8-11 and the circuit 9-10-11-8-6-7 supplies the structure 9-10-11 by means of the coil 10, which being common to both circuits operates as an auto transformer. In Fig. 2 the same relations hold for both of the coils 10 and 12 act as auto transformers.

It will be seen (Fig. 2) that the circuits 7-6-12 and 9-10-6-7 are very closely coupled to the circuit 9-10-12, for aside from the electro-magnetic coupling present in the oscillation transformers 10 and 12, there is a capacity coupling between the wires comprising the antennæ 7 and 9. This close coupling causes the system to be practically inoperative when any other than the quenched gap is used. With an ordinary gap in air, each primary system sets up oscillations of two different frequencies so that there are four coupling waves and these are of such a character as to be opposite to each other. Further, with an ordinary gap in air, in which the oscillations are not quenched, the branch 7 carries current in one direction and the branch 9 also carries current but in the opposite direction as in a loop antenna, thus causing the phenomena found in such an antenna, *i. e.*, the non-radiation of the fundamental oscillation.

As a result of extensive experiments I have found that a form or type of impulse excitation exists when a quenched gap is employed in an oscillatory system which is designed in such relation to the current supply system that a rapid succession of discharges occurs during the flow of each alternating current wave. The quenching of the primary oscillations under these conditions, *i. e.*, high group frequencies, is no

longer dependent upon the reaction of a secondary circuit as in the case of the well known quenched gap phenomena, but is determined solely by the supply current, the gap and the constants of the primary oscillatory circuit. The higher the group frequency the greater the decrement will be of each individual discharge, so that in place of a true quenched gap action, a type of impulse excitation is produced by my system.

By using a quenched gap in the manner described with the apparatus arranged as shown desirable ends are secured, and the detrimental effects found with a single gap in air are eliminated, because current flow exists in the primary systems 7-6-12 and 9-10-6-7 for the very brief period of the first few oscillations. The primary circuits are thus rendered electrically open by the gap for the time period between primary discharges and no oscillations are induced in them by the secondary oscillations. This leaves the structure 9-10-12 free to undergo oscillations that are damped only by radiation; the time period of such oscillations being determined by the capacity and inductance of the circuit 9-10-12.

There is no effective radiation from the circuits 7-6-12 and 9-10-6-7 owing to the brief period of their oscillations and because the quenched gap effectively opens said circuits after the first few oscillations, owing to the very high damping of the primary oscillations that occurs when the group frequency is high.

By employing high group frequency the capacities of the system are charged and discharged at a high rate, 10,000 to 20,000 times per second, thus permitting a large amount of energy to be absorbed and radiated by the system.

Finally, owing to the high group frequency of highly damped primary oscillations, the radiating circuit 9-10-12 is caused to execute practically sustained oscillations throughout the period of each alternating current wave.

With the inductances 10 and 12 adjusted for maximum radiation from the structure 9-10-12, the natural periods of the circuits 7-6-12 and 9-10-6-7 will be found to differ from the natural period of the circuit 9-10-12. In one case for example, maximum radiation was found with the circuit 7-6-12 presenting the frequency of a 745-meter wave, while the circuit 9-10-6-7 had the frequency of a 1100-meter wave and the circuit 9-10-12 radiated a wave of 940 meters.

True syntony or resonance does not exist in my system as in other coupled systems such as those in which the time periods of the primary and secondary oscillatory circuits are the same or are octaves of each other. In my system both the primary cir-

cuits must be dissonant with the radiating circuit when maximum radiation occurs, the degree of this dissonance varying, according to the conditions in the gap, from fifteen to twenty per cent. It may be further noted that in such prior systems as those above indicated, a well defined tuning adjustment exists, so that the energy transferred from the primary to the secondary is a maximum only when a certain critical adjustment of the constants of either circuit is made. In my system on the other hand, owing to the fact that a form or type of impulse excitation exists, there are no critical adjustments for maximum radiation and while a maximum can be found, it exists throughout broad adjustments of the circuits.

As this application possesses matter in common with an application filed by me December 4, 1913, Serial No. 56,108, it is to be treated as a continuation of said prior application as far as such common subject matter is concerned.

I claim:

1. A system including extended main and auxiliary elevated conductors; means for causing quenched electric oscillations in one of said conductors; and an oscillation transformer inductively connecting the conductors. 90
2. A transmitting system including extended main and auxiliary elevated conductors; means for causing quenched electric oscillations in one of said conductors; and a grounded oscillation transformer connected to both of said conductors. 95
3. A transmitting system including main and auxiliary elevated conductors mounted adjacent each other; means for causing a quenched oscillatory current flow in one of said conductors; and a grounded oscillation transformer connected to both of the conductors. 100
4. A transmitting system including extended main and auxiliary elevated conductors respectively forming parts of different circuits; means including a quenched spark gap for setting up electric oscillations in one of said conductors; and a transformer connected to both of said conductors. 110
5. An oscillatory system including extended main and auxiliary elevated conductors mounted adjacent each other to form two oscillatory circuits; a quenched gap connected to said circuits; and a radiative circuit electrically coupled to said two oscillatory circuits. 120
6. A system comprising an oscillatory circuit and a radiating circuit including substantially parallel elevated conductors extending adjacent each other; with means including a grounded transformer for inductively connecting said two circuits. 125
7. A system including extended main and auxiliary elevated conductors; means for

- setting up a quenched oscillatory current flow in one of said conductors; an auto transformer in circuit with the other conductor; and an oscillation transformer inductively connecting said two conductors. 5
8. A system consisting of main and auxiliary sets of conductors; means for setting up quenched electric oscillations in that part of the system including one of said sets of 10 conductors; a coil connected between said set of conductors and the ground; a second coil in inductive relation with the first coil and connected between the ground and the second set of conductors; with a variable 15 inductance also including in circuit with said second set of conductors.
9. An oscillatory system consisting of a plurality of open oscillatory circuits; a radiating circuit coupled to said oscillatory 20 circuits; means for transferring energy from said oscillatory circuits to the radiating circuit; and means for preventing said radiating circuit from inducing current in said open circuits.
10. An oscillatory system consisting of a plurality of open oscillatory circuits; a radiating circuit coupled to said oscillatory circuits; means for transferring energy from said oscillatory circuits to the radiating 25 circuit; and means for preventing effectual radiation from the open circuits. 30
11. An oscillatory system consisting of elevated conductors forming a plurality of primary circuits and having parts associated to provide a radiating circuit coupled to said primary circuits; means for transferring energy from said primary circuits to the radiating circuit; and means for preventing said radiating circuit from inducing current in said primary circuits. 35
12. An oscillatory system consisting of elevated conductors forming a plurality of primary circuits and having parts associated to constitute a radiating circuit coupled to said primary circuits; means for transferring energy from said primary circuits to the radiating circuit; and means for preventing effectual radiation from parts of 40 said system other than the radiating circuit. 45
13. A transmitting system consisting of a plurality of primary circuits having portions associated to constitute a radiating circuit, said primary circuits being out of resonance with said radiating circuit and the latter being coupled to the primary circuits 50 under conditions of maximum radiation. 55
14. A transmitting system consisting of a plurality of primary circuits; a radiating circuit coupled to said primary circuits; with means including a quenched gap for causing in said primary circuits an oscillatory current flow quenched by means other than the reaction of the radiating circuit. 60
